LAWRENCE H. MORSE AND CLIFTON CHISHOLM, OF CLEVELAND, OHIO, ASSIGNEES TO THE AMERICAN MULTIGRAPH COMPANY, OF CLEVELAND, OHIO, A CORPORATION OF OHIO.

TABULATING ATTACHMENT FOR KEYBOARD MACHINES.

Application filed November 6, 1925. Serial No. 67,198.

This invention relates to an attachment for various keyboard machines of the type wherein each actuation of a key, besides performing certain work, results in a feed of a certain distance between the material and device acting on such material. Our invention is well adapted for embodiment for example, with an embossing machine for producing printing strips wherein the keyboard controls the mechanism which accomplishes the embossing and causes a letter feed for each key actuated.

One of the objects of the invention is to provide effective mechanism for causing the machine when once actuated, to feed a selected number of letter spaces automatically. Such feed may be without effect on the material or may be accompanied by a repeated forming of the same character.

Another object of our invention is to provide a suitable visible indicator available to the operator at all times to indicate the progress of the feed, whether the material be acted on or not. Still another object is to provide an audible warning signal to indicate to the operator when the operation on the material is near the end of a line, so that he may properly conclude that line at the end of a word or syllable.

Our mechanism may have a number of adjustably positioned stops, whereby in the operation of the machine the matter being formed may be readily located in a series of definitely positioned laterally spaced regions.

For instance in making a form of names and several columns of figures it is possible that by means of our mechanism to enable the forming of the name, then spacing to a definite location for the first column, then forming of the figures in that column in proper position to align with the figures on another strip, and so on with succeeding columns.

If it be desired to set up a form wherein the lines are separated into transverse rules, our tabulator mechanism assists in the forming of different strips of definitely selected length, irrespective of the number of characters thereon, so that the various line sections will terminate at the transverse rules.

All of the above features of our invention, as well as others, will be hereinafter more fully explained in connection with the embodiment illustrated in the drawings. The

essential novel characteristics of the invention are summarized in the claims.

In the drawings, Fig. 1 is a plan of an embossing machine corresponding to Patent No. 1,557,754 equipped with our tabulator; Fig. 2 is a side elevation with the machine so equipped; Fig. 3 is a cross-section of the tabulator on a vertical plane indicated by the line 3-3 on Figs. 1 and 5; Fig. 4 is a detail of a brake on the tabulator, being a substantially horizontal section on the line 4-4 of Fig. 3; Fig. 5 is a plan of the tabulating mechanism removed; Fig. 6 is a side elevation of such tabulator, looking from the left hand side of Fig. 1; Figs. 7 and 8 are plans of the tabulator with certain parts broken away and omitted, these views illustrating the same parts in different positions; Fig. 9 is a side elevation of the tabulated mechanism looking from the right hand side of Fig. 1; Fig. 10 is a transverse vertical section of the embossing machine as indicated by the line 10-10 in Fig. 1.

In order that our tabulating attachment may be better understood, we will first describe briefly the embossing machine illustrated in Figs. 1, 2 and 10, although it is to be understood our invention is not limited to coaction with that particular type of machine.

The embossing machine shown comprises a suitable bed 9, a transversely reciprocable die carrier 10, having individually movable male and female dies 11, a keyboard 12, and suitable mechanism controlled by the keyboard for positioning the die carrier and consequent upon such positioning automatically plunging the selected dies toward each other to emboss an intermediate strip of metal 13, which is fed from a suitable reel 14 and flanged at its edges by intermittently operated rolls 15. Such flanged strip passes along a supporting rail 16 behind a retaining rail 17, both extending through an open longitudinal space in the die carrier. These rails are cut away at the central portion 18 where the selected dies operate to effect the embossing.

To reciprocate the die head of this Chisholm embossing machine there are provided a pair of solenoids 20 operating on a common core bar 21 connected by a link and lever 22 with the die head, the solenoid on either side being energized whenever a key in the corresponding half of the keyboard is depressed. The die carrier, thus shifted from its central

position of rest, is stopped in selected position by means of the raised rear end of a key lever 25, which coacts with a suitable latch on the die carrier. Fig. 10 shows the 5 rear end of the shearing key lever 26, hereinafter more fully described, which in this respect acts similarly to an embossing key lever. Fig. 1 indicates at 65 a pair of levers for closing the solenoid switches when a key 10 is depressed. Each of these levers carries a rod 66 overhanging the rear portions of these key levers.

As the die carrier moves toward such raised rear end of an actuated key lever, the 15 plunger 30 having an inclined lower end, engages the key lever and is raised thereby to actuate the plunging mechanism about to be described. After this plunger 30 passes over the key lever, the die carrier is stopped 20 by engaging the resilient abutment 32 and then the plunger 30 descends to rest behind the key lever, so that the die carrier becomes locked in a definite position with the dies corresponding to the actuated key in the central 25 or embossing position.

The raising of the plunger 30 swings a bail 35, which by means of a link 36 and a bell crank 37 withdraws the rod 38 from a single-rotation clutch 40. This clutch, thus freed, 30 clutches the continuously rotating main driving pulley 47 to the shaft 41 which carries a pair of crown cams indicated at 42 in Fig. 2 which operate on the lower end of intermediate pivoted levers 43 and 44, which act 35 to shove inwardly suitable plungers 45 and 46, which engage the outer ends of the selected female and male dies respectively, or the shearing dies, one of which (48) is shown in Fig. 10.

40 Following the embossing operation the plunging mechanism returns to normal position, spring fingers 50 on the die head return the dies, the key returns, the circuit to the energized solenoid is opened and the carrier is returned to normal position under the influence of a compression spring 51 on either side of the carrier. During these return operations, the strip is fed toward the right a distance of one character by means of the 45 rolls 15. As shown one of these rolls carries a ratchet 52 operated by a pawl 53 on a suitable lever connected by a link 54 with a rock arm 56 on the rock shaft 55, which also carries the die operating lever 43.

55 The mechanism for returning the key levers, shown in Fig. 2 comprises a hook 60 on the embossing lever 43, which on the return or outward stroke engages the upper end of a pivoted latch plate 61, the lower end of 60 which extends beneath a tooth on a raised key lever. When this lower end is withdrawn the key lever is freed and the lever is suitably returned.

65 90 in Figs. 1, 2 and 5 indicates a shearing key located at the keyboard on the forward

end of the key lever 26. This key lever operates to shift the die head and stop it and initiate the operation of the clutch the same as already described for the character keys. The shearing dies are indicated at 48 in Fig. 70 10. When they are brought into position, and the clutch operated, the embossing levers 43 and 44 operate to plunge these dies toward each other, thus cutting the metal strip in two and leaving free the embossed line strip 75 indicated at 13 in Figs. 1 and 10.

The forward embossing arm 43 and the shearing key 90 above referred to are connected with our tabulator mechanism about to be described, and operate respectively to 80 feed the tabulator mechanism step by step for each stroke of the embossing arms and to restore the tabulator mechanism when the shearing key is operated.

Referring now to the tabulator mechanism 85 proper, the frame of this consists of an inclined plate 120 mounted on a bracket 121 secured to the bed 9 of the embossing machine. Rigidly mounted in the plate is a stationary stud 122 projecting upwardly at right angles 90 to the plate. This stud is shown as anchored to the plate by a pin 123 Fig. 3, which also rigidly anchors the bushing 125 surrounding the pin. The upper portion of the pin is flattened and carries rigidly a collar 126, a 95 pointer 127, a washer 128 and a nut 129. The tabulator includes a number of rotative elements surrounding the bushing 125 and retained between the plate 120 and the collar 126. These will now be described.

100 Journalled on the bushing 125 is a sleeve 130 having an internal annular space about the bushing and a somewhat larger space about the pin 122 above the bushing. In the latter space is a ring 131 having an external contour materially smaller than the adjacent bore of the sleeve and having a central opening 133 materially larger than the external diameter of the pin. This ring 131 is pivoted by means of a pin 135 to the stationary collar 126. A helical spring 137 surrounds the barrel portion of the bushing 125 and is anchored at its upper end to the ring 131 at 138 and at its lower end to the hub portion of the sleeve 130. The helical spring tends to return the sleeve when it is relatively displaced from normal position. Such relative displacement swings the ring 131 about its pivot into engagement with the inner surface of the sleeve so that this ring acts as a brake retarding the return of the sleeve, the degree of the braking action being commensurate to the extent that the sleeve is displaced. The purpose of this will hereinafter be described.

110 Rigidly secured to the rotatable sleeve 130 are the following members, best shown in Fig. 3, namely a ratchet wheel 140 (shown as bearing against a flange 139 on the exterior of the sleeve), a disk 141 below the ratchet 115

wheel, and riveted to it, an externally toothed disk (similar to a gear wheel) 143 shown as resting on the sleeve flange 139, a collar 145 above the toothed disk and a pair of 5 mounting circular plates 146 and 147 above the collar 145. These parts may be all held together by screw bolts 148 shown as passing through the plates, the collar and the notched disk and threaded into the ratchet wheel, and thus clamping the parts onto opposite sides 10 of the flange 139 on the sleeve.

The toothed disk 143 has on its upper face an annular groove 149. In this groove seats a corresponding arcuate rib 151 on the under-side of a block 150, which is held between the toothed disk and the plate 146. Threaded into this block 150 and extending upwardly from it is a screw 153 on which is mounted a knob 154. A spring 155 is a recess in the knob and 15 beneath the head of the screw tends to hold the knob in the position shown. When in that position, a pin 157 carried by the knob and extending through an opening in the block 150 occupies the space between two adjacent teeth on the disk 143. The purpose 20 of this construction is to lock the block 150 in any desired position on the disk. By pulling upwardly on the knob 154 its pin 157 is freed from the disk 143, and then the block 25 may be shifted in an arcuate direction as desired and locked in a position by returning the pin between selected teeth.

The tabulator mechanism, as hereinafter explained causes the toothed disk 143 to be 30 rotated for each embossing cycle of operation of the embossing machine a distance corresponding to one tooth, and accordingly if the block 150 be set back from a suitable stop a certain number of teeth, the embossing machine 35 may operate continuously for a corresponding number of strokes, feeding the ribbon a corresponding number of letter spaces, whereupon the block 150 will engage the stop and the feeding operation cease. 40 This action of the stop will be hereinafter explained in detail.

Rotatively mounted on the stationary tabulator bushing 125 is a flat bar or rocking plate 160. To the right hand of this bar is anchored a tension spring 161 tending to rotate the bar in the left hand direction. Nearly diametrically opposite from this spring is an extension 163 of the bar which bears against the rear side of an intermediately pivoted 50 lever 165, the lower end of which is connected by a link 166 with the upper portion of the embossing lever 43. It will be remembered that the return or feed stroke of the upper end of this lever effects the feeding of the 55 ribbon a distance corresponding to one letter. The same movement, by reason of the link 166 and lever 165, will release the bar 160 so that its spring 161 may turn it a short 60 distance. The bar 160 carries a pawl 170 pressed by a spring 171 into engagement with

the ratchet wheel 140. Accordingly as the embosser arm swings on the return stroke, the spring 160 through the bar and pawl turns the ratchet 140 a distance corresponding to one tooth. This turns the toothed wheel 143 70 one tooth and carries the block 150 one step nearer its stop. A detent pawl 175 pivoted on the plate 120 and pressed toward the ratchet wheel by a spring 176 retains the gain 75 made by the pawl 170. The mechanism accordingly provides an indicator for the number of cycles of the embossing machine moving one space with each cycle, whether the embosser movement be initiated by a character key, the space key, or the tabulating 80 key hereinafter described.

The stop above referred to with which the traveling block 150 cooperates comprises a block 180 pivoted on a lever 181 which is pivoted at 182 to the stationary plate 120. A 85 spring 184 acting on this block tends to keep it against a stop pin 185 on the lever. A spring 186 normally maintains the lever in engagement with a stationary abutment 187 carried by the plate 120. Bearing against 90 the rear edge of the lever 181 is the upper end of a lever 190 (Fig. 9), pivoted at 191 to a downwardly extending ear 193 of the plate 120. The lower arm of this lever 190 is notched as at 195 and coacts with the pin 201 95 on a side of a key lever 200 which we call the tabulating lever. This lever has a finger key 202, shown as suitably accessible at the front and right hand side of the tabulating 100 mechanism. The lever is pivoted at 205 to a stationary portion of the embossing machine and at its rear end has a pin or projection 206 underlying the bail 35, the raising of which operates to release the clutch of the embosser.

Assuming that the stop 150 has been manually set a distance from the block 180 (measured by the number of teeth of disk 143) in accordance with the number of strokes desired, the key 202 may be depressed thus raising the bail 35, which releases the clutch and starts the operation of the embossing levers. As soon as the key is actuated the pin 201 105 carried thereby comes below the shoulder of the notch 195 on the lever 190 and accordingly the lower end of this lever swings rearwardly carrying the shoulder above the pin into the position shown in broken lines in Fig. 9, the upper end of the lever coming against the bar 181 as shown in Fig. 7. The shoulder of the notch 195 thus holds the tabulator lever depressed, which holds the bail elevated. Accordingly, the clutch does 110 not pass out of coaction at the end of a rotation as normally, but continues for successive rotations. Each rotation of the clutch by means of the outward stroke of the embossing lever 143, feeds the ratchet wheel 140 and the notched disk 143 one tooth, gradually carrying the block 150 step by 115 step toward the block 180. After the desired 120

number of rotations has been completed, lacking one rotation, an inclined face 210 of the block 150 engages an incline 211 of the block 180, and thus cams backwardly the lever 181, rocking the lever 190 and withdrawing its lower end from above the pin 201, whereupon the tabulator lever 200 is released and rises to normal position (by means of the clutch and spring 39 pulling downwardly on the bail) and thus replaces the pin 201 behind the lever 190.

Now the clutch goes on for one rotation more and then automatically stops itself by reason of the normal return of the clutch operating rod 38. During this final rotation the end of the block 150 is carried clear of the block 180 and then later returns to normal position under the influence of the spring 186.

20 The arm 181 carries a spring arm 220 on which is mounted a hammer 221 coacting with a gong 222 mounted on an extension of the plate 120. The hammer normally lies against the gong but as the block 150 forces 25 the arm 181 rearwardly the hammer is carried away from the gong and then as the block 150 clears the block 180, the hammer returns and strikes the gong, thus notifying the operator that the selected feed of the 30 ribbon has been completed.

After the completion of the tabulator operation (either immediately or after the subsequent actuation of a key or keys in the keyboard) a shearing key of the embossing 35 machine is actuated to cut off the portion of the strip already embossed, so that it may be discharged from the machine. Such shearing key, located in the embosser keyboard and designated 90, is coupled with the tabulator 40 mechanism to restore it to normal position, as follows.

Connected to the shank of the shearing key 90 (Figs. 2 and 6) is the forward arm 45 of a bell crank 230 pivoted to a down turned portion 231 of the plate 120 and having an upwardly extending arm 232 standing behind an arm 234 on a rocking plate 235 pivoted to the plate 120 by a screw 236. A spring 237 tends to keep the arm 234 in engagement with the bell crank arm 232. Whenever the shearing key is operated, the 50 plate 235 is accordingly rocked and this rocking action accomplishes several results, as follows:

55 It will be noticed from Fig. 8 that the right hand edge of the plate 235 near the free end is concaved and normally bears against the periphery of the disk 141 and by reason of the spring 237 forms a friction brake, preventing the forward stroke of the embossing 60 lever 43 from overfeeding the ratchet wheel and associated parts by momentum, but when the shearing key rocks this plate, this brake shoe is removed from the disk, as shown in Fig. 8. At the same time, an edge 238 of the

plate 235 engages a pin 239 on the feeding pawl 170 and forces it to idle position, as shown in Fig. 8. At the same time an edge 240 on the plate engages a pin 241 on the pawl 175 and forces it to idle position as shown 70 also in Fig. 8.

When the two pawls 170 and 175 are withdrawn from the ratchet wheel as just explained, the wheel is free to rotate and it is thus driven back to idle position by the helical spring 137, which was gradually wound up as the ratchet wheel was rotated step by step. As the parts start returning the stop 150 rocks the stop 180 on its pivot and passes beyond it. During the return movement as 80 heretofore explained, the ring 131 acts as a brake retarding the movement and preventing the delivery of a blow. The farther the ratchet wheel has turned the parts, the more is the spring wound up, giving more force for 85 the return movement, but to the same extent the force of brake is increased, the result being that irrespective of the degree of turning of the parts, they come back gently to position when released.

90 The disk 141 riveted to the underside of the ratchet wheel has a continuous cylindrical wall with the exception of one notch 250 therein. Normally the pawl 251 bears against the periphery of this disk, under the influence of the end portion of the spring 176 which bears against a pin 252 on this pawl. However, when the parts return to normal position, the notch 250 comes into registration with the nose of the pawl 251, and the pawl springs into the position shown in Fig. 8, thus stopping the parts in definite position.

95 In order that the releasing plate 235 may remain in the retracted position after the pressure on the shearing key is relieved, we provide a locking dog 260 pivoted to the plate 120 at 261 and having a lip 262 which normally occupies a recess 263 at the edge of the plate 235, as shown in Fig. 7. When however, the plate 235 is rocked by the shearing key, the 100 pressure of the spring 237 against a pin 264 carried by the dog 260 swings the latter to the position shown in Fig. 8, where the lip 262 engages a shoulder on the plate and retains it in this withdrawn position.

105 In the released position of the parts as just described, and as shown in Fig. 8, the nose 265 of the dog 260 bears against a recessed edge of the operating bar 160. The next operation of this bar cams the dog 260 back to position to 110 free the plate 235, which thus swings into its braking position and this restores the pawls 170 and 175 to the operative position shown in Fig. 7.

115 Accordingly, following the release of the 120 tabulator pawls and the spring return of the relating parts as already explained, the first embossing operation results in setting the tabulator operating mechanism without feeding the relative parts. To make the indicator ac- 125

curate therefore, the dial graduation is normally spaced one space from the pointer; that is to say, one cycle of operation is required to bring the dial to the zero position. Each subsequent cycle of operation of the embossing machine turns the dial one space. This goes on throughout the operation of the embossing machine until the shearing key is operated, irrespective of whether the tabulator key is used. Accordingly the dial forms a convenient indicator of the progress of the embossing operation.

We have referred to the stationary pointer 127 carried by the stationary stud 122. This pointer coacts with suitable radial marking on the plate 147 as shown in Fig. 5. The graduation marks enable the block 150 to be readily positioned for any number of strokes desired, and then the pointer in coaction with such graduations as the dial rotates, shows at a glance the number of strokes the machine has made. For instance, if it is desired to start numeral work at 20 spaces from the beginning, the block 150 will be set at the mark "20" 25 on the dial 147, then as the tabulator operates, the dial will rotate in the left hand direction past the pointer. When for instance the numeral "15" passes the pointer, the operator will see that he has space for five more characters.

As heretofore intimated, our mechanism is very useful as an indicator even though the tabulating key be not used. The dial is located directly in front of the operating keyboard where it may be readily observed and always indicates the length of the ribbon which has passed the embossing position. It is useful for this purpose whether the maximum length of ribbon be embossed by a continuous operation of the keyboard, or the tabulator effect intermittent feeding action successively, or whether the metal ribbon is cut off in several short sections. Likewise, the gong is always useful in warning the operator that he is near the end of a line, irrespective of whether he is performing any tabulating operation.

For simplicity we have described the operation of the tabulator with reference to one stop 150 mounted on the rotative mechanism and for many uses such single stop is valuable. However, for column work involving numerals, it is frequently desirable to have several stops and our mechanism may carry as many of such stops, similar to the stop 150, as desired. Fig. 5 shows two stops and is intended to illustrate any convenient number.

If the form to be embossed comprises for instance a list of names and three columns of figures, the operator will ordinarily employ three tabulator stops and will set the first one at a distance from the pointer to provide for a sufficient number of characters to accommodate the longest line of letters; then

the second one will be a distance beyond that sufficient for the largest numeral, and the third one a correspondingly selected distance beyond the second. In forming the embossing lines when the tabulator is so set, the operator will ordinarily write the word portion of the line, then press the tabulator key, causing mere spaces until the line is completed to the desired length. He is advised thereof by the striking of the gong, and then he writes the first numeral portion. If he desires he then presses the tabulator key to fill out the line and writes the second numeral portion when that is completed to the desired length he operates the shearing key which cuts off the completed line ready for delivery from the embosser for mounting in a printing form.

If the operator desires to make up a form with separate strips, so that they may be separated by suitable rules for instance, it is very convenient to use one tabulator stop for the length of the name portion of a form, and type first all of the lines in the name column shearing each when completed; then reset the tabulator and type and shear off the numeral lines of the first numeral column, repeating this for each successive column of numerals. These various columns of names and numerals may be delivered directly as formed onto a suitable blanket, for instance by the mechanism shown in Patent No. 1,557,811 issued October 20th to our assignee The American Multigraph Company, such receiving blanket being turned back to initial position with the starting of each column.

It will be seen from the above, that our tabulator may be used for successive tabulating actions on a single line strip, sheared at the end of the complete line, or different columns may be readily produced separately, shearing occurring at each column. By causing the tabulator restoration to take place automatically consequent upon the shearing, the operator has the alternative of running his line continuously across the page, tabulating it as it is written, or of shearing it into successive lengths, automatically resetting the tabulator each time.

Our tabulator is also of use for causing a repetition of an embossing character; thus if it be desired to print a succession of hyphens as a lead line for instance, the hyphen key is struck and immediately thereafter, or simultaneously therewith, the tabulator key resulting in a succession of hyphens being embossed, until the stop comes into action. As another instance, the mechanism might be used for producing ciphers in a column of long numerals.

Finally, it may be remarked that our tabulator mechanism is very compact and readily mounted in available space behind the keyboard of the machine, and need not require

any change in the form or position of the machine parts, but may be coupled directly with existing machines, as illustrated herein.

Having described our invention, we claim:

5. 1. The combination with means for embossing characters and means for holding material to be embossed, of means for feeding one of said means with reference to the other, and a tabulating mechanism comprising: a settable device, and power mechanism coupled with the feeding mechanism for automatically moving the settable device from its set position by steps of fixed amount but of variable number to a stop, thereby regulating the number of feeding movements.

2. The combination with means for holding embossing letter character dies, means for holding material to be embossed, mechanism for feeding one of said means with reference to the other a letter space at a time, and a settable tabulator mechanism adapted to cause by manually released power a selected number of operations of said mechanism.

3. The combination with embossing mechanism, including cooperating sets of male and female dies, means for guiding between them a ribbon of material to be embossed, and for feeding the material step by step, and a tabulating mechanism adapted to be set to cause automatically a selected number of step by step feeding movements of the ribbon feeding mechanism.

4. The combination of cooperating sets of male and female dies, a corresponding keyboard, means actuated thereby for selecting a pair of dies, means for guiding between the selected dies a ribbon of material to be embossed, means for operating the dies to effect the embossing, means for feeding the material step by step, consequent upon the actuation of the embossing mechanism, and a tabulating mechanism adapted to be set to cause automatically a succession of step by step feeding movements.

45. 5. The combination with letter and numeral character forming devices, of mechanism for operating the same, mechanism driven by such operating mechanism for causing a character feed, and settable tabulating mechanism connected with said operating mechanism for automatically causing a selected number of letter feeds.

6. The combination with a keyboard, of corresponding character forming devices, means adapted to operate the same, means for guiding material to be acted on by said devices, feeding mechanism actuated by said operating means a character space at a time, and a settable tabulator mechanism adapted when set and released to cause a succession of similar strokes of said operating means according to the setting of the tabulator.

7. The combination with embossing dies, an embossing lever adapted to operate the same, mechanism connected with said lever

for feeding material to be embossed, and tabulating mechanism arranged to control the operations of the lever for automatically giving a predetermined number of successive feeds to said material.

8. The combination with embossing dies, a rocking lever arm adapted to operate the same, means for guiding between the dies a ribbon to be embossed, ribbon feeding mechanism actuated by the return stroke of the embossing arm, and a settable tabulator mechanism adapted to cause successive strokes of said embossing arm according to the setting of the tabulator.

9. The combination with embossing dies, mechanism adapted to operate the same, means for guiding material to be embossed, feeding mechanism actuated by such operating mechanism to feed the material the same space for each actuation, a settable tabulator mechanism adapted to be set to cause a selected number of strokes of said operating mechanism to actuate said feeding mechanism according to the setting of the tabulator, and a key to initiate the movement of the tabulator.

10. The combination with a series of work-performing members, mechanism for operating the same, a keyboard having keys adapted to select members corresponding thereto, a universal member actuated by any of the keys for initiating the mechanism which operates the members, and settable tabulator mechanism including a tabulator key adapted to actuate the universal member to cause a predetermined number of repeated operations of the operating mechanism.

11. The combination with embossing dies, mechanism for operating the same, a keyboard having keys adapted to determine the character to be embossed, a universal member actuated by any of the keys for initiating the mechanism which effects the embossing, a tabulator key adapted to actuate the universal member to cause actuation of the embossing mechanism, and a settable device to determine the number of repeated actuations so caused.

12. The combination of a set of individually different work performing members, a keyboard having keys corresponding to the members respectively, means whereby a key selects the corresponding member, feeding mechanism for moving the material to be acted on normally disconnected power means and a clutch for operating the feeding mechanism, means initiated by any key for releasing the clutch, and a tabulator mechanism adapted to be set to cause a selected number of operations of the feeding mechanism, and a key for releasing the clutch to initiate the movement of the tabulator feeding mechanism.

13. The combination of embossing dies, a keyboard having keys adapted to select the same, mechanism for operating selected dies

including a continuously driven member and a clutch, a member actuated consequent upon the selection for releasing the clutch, and a settable tabulator mechanism having a key for releasing the clutch to cause successive operations thereof according to the setting of the tabulator mechanism.

14. The combination of a reciprocable die head carrying embossing dies, a keyboard having keys adapted to initiate the reciprocation of the die head, a latch adapted to contact with an actuating key to stop the die head in corresponding position, mechanism for operating positioned dies including a continuously driven member and a single rotation clutch, a member actuated by said latch for releasing the clutch, and a settable tabulator mechanism having a key to release the clutch and cause successive rotations thereof according to the setting of the tabulator mechanism.

15. The combination with a keyboard controlled machine having individual character members and having a feed for material for causing successive actions by the members to take place on the material one space ahead of the preceding action, a tabulator having a movable member automatically moved one step by each operation of the feed, means associated with the tabulator for causing continuous operation of the feed, and means actuated by said movable member coming to a definite position for stopping the continuous operation.

16. The combination with means for holding embossing dies, means for guiding material to be embossed, means for positioning one of these means with reference to the other to select the character to be embossed on the material, means for operating the dies, means for causing a letter feed consequent upon an embossing operation of the operating means and a tabulator mechanism adapted to cause a succession of letter feeds consequent upon an idle operation of the operating means and including a settable stop on the tabulating mechanism for limiting such number of such feeds.

17. The combination with a keyboard of corresponding male and female dies, means for guiding a ribbon of material between the male and female dies respectively, means for operating the dies and feeding the material step by step including a normally disconnected rotary driver and a single rotation clutch, a universal member for releasing the clutch adapted to be actuated by any key, a tabulator mechanism having a settable stop, a tabulator key adapted to move the universal member to release the clutch and hold it released, said tabulator having mechanism whereby it may be moved for each feeding operation until the settable stop engages a cooperating stopping member.

18. The combination with a reciprocable die head, male and female dies mounted

thereon, means for guiding a ribbon of material lengthwise of the die head between the male and female dies respectively, a keyboard, mechanism operated thereby for positioning the die head including a latch movable with the die head, a universal member operated by said latch, normally disconnected driving means including a rotary member and a single rotation clutch, means whereby said driving means operates the dies and gives a periodic feed to the ribbon, a universal member releasing the clutch adapted to be operated by the latch, a tabulator mechanism having a settable stop, a tabulator key adapted to move the universal member to release the clutch and hold it released, said tabulator having mechanism whereby it may be moved for each feeding operation until the settable stop engages a cooperating member.

19. The combination with members adapted to act on material, of letter feed mechanism, a tabulating device adapted to cause automatically successive operations of the letter feed mechanism, means for separating the material acted on from the rest of the material, and means whereby the operation of this separating means restores the tabulating mechanism.

20. The combination of embossing mechanism having a keyboard, embossing dies actuated thereby to emboss material, a letter feed mechanism, a tabulating device adapted to cause automatically successive operations of the letter feed mechanism, means for cutting off the embossed material, and means whereby the operation of this cutting off means restores the tabulating mechanism.

21. The combination with embossing dies, means for operating the same to emboss material interposed therebetween, mechanism for causing a letter feed consequent upon the operation of the embossing mechanism, a tabulator mechanism having a key adapted to cause successive operations of the letter feed, said tabulator mechanism having a settable stop, and means whereby each operation of the letter feed brings the stop one step nearer a definite point and means operated by the stop arriving at the definite point for terminating the letter feed, mechanism for shearing the embossed material, the connection of said shearing to the tabulator to restore it consequent upon the operation of the shearing mechanism.

22. The combination of embossing dies, an embossing lever adapted to operate the same, a letter feed device connected with said lever, tabulator mechanism connected with said lever and adapted to operate for each letter feed, mechanism associated with the tabulator for initiating repeated operation of the letter feed mechanism, and mechanism in the tabulator gradually reset by the successive operations of the embossing lever to termi-

nate the successive feeds, a shearing device and mechanism connecting the same with the tabulator to restore the tabulator.

23. The combination with embossing dies, 5 a die head carrying the same, a keyboard having finger keys corresponding to the respective dies, mechanism whereby the actuation of a key correspondingly positions a die, mechanism for moving said dies toward each 10 other to emboss interposed material, means for guiding said material, means for automatically feeding the material a letter space at a time, a tabulator mechanism adapted to be set to cause a definite number of repeated 15 actuations of the letter feed, a shearing key in the keyboard adapted when actuated to cut off the embossed material, and a connection between the shear key and tabulator to release the latter when the shear key is operated.
- 20 24. The combination, with a keyboard controlled machine having individual character members and a letter feed, of a tabulator having a rotary disk, a ratchet connection between the disk and said machine, so arranged 25 that the disk is rotated one step for each operation of the letter feed, an adjustable stop on said disk, and a member with which the stop cooperates to terminate operations of the letter feed.

- 30 25. The combination with mechanism having a periodic feed, of a tabulator having a rotary disk, a ratchet connection between the disk and the feeding mechanism whereby the disk is rotated one step with each operation 35 of the letter feed, an adjustable stop on said disk, a member with which the stop cooperates to terminate operations of the feeding mechanism, a tabulator key adapted when actuated to cause repeated action of the feeding mechanism, and mechanism operable by 40 means of the adjustable stop coming to a definite position for releasing the tabulator key.

- 45 26. The combination with character forming mechanism and a letter feed for feeding material with reference thereto, of a tabulator having a rotary disk, a ratchet feed for said disk, operating consequent upon the letter feed, an arcuately adjustable stop on said 50 disk, a mechanism for causing repeated operations of the letter feed, and a movable member engaged to operate by said adjustable stop coming to a certain position for releasing the mechanism which causes the repeated 55 operation.

- 60 27. The combination with a keyboard machine having a cycle of operation for each actuation of a key, a tabulator mechanism comprising a movable member and cooperating 65 means to feed said member periodically one step for each cycle, mechanism associated with the tabulator mechanism for causing repeated cycles of operation for one actuation of a keyboard key, a stop adjustable on said movable member, and a cooperating stop op-

erated by the adjustable stop coming to a definite position, and operating to withdraw the said cooperating means to inactive position.

28. In a tabulator, the combination of a 70 ratchet wheel, a reciprocating member having a pawl for operating the wheel step by step, a notched disk rotatable with the wheel, an arcuately adjustable stop on the disk, means for locking it with reference to a selected notch on the disk, a tabulator key adapted when actuated to remain in the actuated position for successive strokes of the reciprocating member, and means operated by the adjustable stop coming to a definite 75 position to release the tabulator key.

29. In a tabulator, the combination of a 80 rotative disk, means for giving it successive partial rotations, an adjustable stop on the disk, a repeat mechanism, means whereby the stop coming to the definite position releases the repeat mechanism, and a spring constrained by the successive rotations of the disk, and means for releasing the disk whereby the spring may return it.

30. In a tabulator, the combination with a 85 suitable support, of a stationary stud carried thereby, a ratchet wheel rotatably mounted thereon, a disk connected with the ratchet wheel, an arcuately adjustable stop on the 90 disk, a repeat mechanism including a setting finger key, means whereby the stop coming to the definite position releases the repeat mechanism, and a spring constrained by the successive rotations of the disk, and means for 100 releasing the disk whereby the spring may return it.

31. In a tabulator mechanism, the combination of a rotary disk, a ratchet feed therefor, an adjustable stop on the disk, repeat 105 mechanism, mechanism for releasing the repeat mechanism actuated by the stop coming to a definite position, a brake preventing the oversetting of the disk by momentum of the ratchet feed, and means for releasing the 110 brake when the disk is to be restored.

32. In a tabulator mechanism, the combination of a rotary disk, an adjustable stop thereon, a ratchet disk connected with said 115 rotary disk, a reciprocating member for operating the ratchet disk, a brake disk rigid with the ratchet disk, a brake shoe coacting therewith for preventing overfeed of the ratchet mechanism, and mechanism for concurrently releasing the same and the ratchet 120 mechanism.

33. The combination with embossing dies, and a reciprocating arm for operating the same, of a tabulator having a member with a ratchet feed operated by the embossing arm, 125 a brake on said member tending to prevent oversetting from the momentum of the embossing arm, means for disconnecting the ratchet feed and releasing the brake.

34. In a tabulator, the combination of a 130

5 rotary disk, an adjustable stop thereon, a ratchet feed for the disk, a returning spring connected with the disk and successively constrained with each feeding movement of the disk, means for releasing the ratchet feed to enable the spring to return the disk, and a brake automatically applied to reduce the shock of the return movement.

10 35. In a tabulator, the combination of a rotary disk, an adjustable stop thereon, a ratchet disk connected with the rotary disk, a reciprocating pawl for feeding the ratchet disk, a spring successively constrained by successive feeding movements of the pawl, and 15 means disconnecting the pawl from the ratchet disk to allow the parts to return, and a brake connected with the returning spring for applying a retarding force commensurate to the force of the spring.

20 36. In a tabulator, the combination of a stud, a rotary sleeve about the same, a helical spring within the sleeve and about the stud and connected to the sleeve and tending to return it to normal position, a disk connected with the sleeve, one or more adjustable tabulator stops on the disk, repeat mechanism for successively giving the disk partial rotations and means for releasing it consequent upon a stop coming to a definite position.

30 37. In a tabulator, the combination of a stationary stud, a rotary sleeve about the same, a helical spring within the sleeve and about the stud and connected to the sleeve and tending to return it to normal position, a disk connected with the sleeve, one or more arcuately adjustable tabulator stops on the disk, a ratchet disk connected with the sleeve, a reciprocating pawl for operating said disk, 40 a tabulator key and mechanism controlled thereby for repeatedly reciprocating the pawl and means for releasing the tabulator key consequent upon a tabulator stop coming to a definite position.

45 38. In a tabulating mechanism, the combination of a stud, a sleeve rotatably mounted thereon, a helical spring within the sleeve connected thereto at one end of the spring, a ring loose within the sleeve pivoted to a stationary member and having the other end of the spring anchored to it, a disk on said sleeve, an adjustably positioned stop carried by the disk, means to feed the disk step by step and thus wind up the spring, tabulating 50 means controlled by the disk and means for releasing the disk.

55 39. In a tabulator, the combination of a rotary disk, one or more arcuately adjustable stops thereon, a ratchet disk connected with the rotary disk, a feeding pawl and a detent pawl coacting with the ratchet disk, keyboard, mechanism having a cycle of operation for each actuation of a key, operating mechanism connecting the same with the feeding

65 pawl, repeat mechanism for causing successive cycles of operation for one key actuation, means whereby one of said stops coming to a certain position may terminate the operation of the repeat mechanism, and mechanism for releasing both pawls from the ratchet disk. 70

75 40. In a tabulator, the combination with a suitable support, a stationary stud carried thereby, a sleeve rotating about the stud, a stationary member carried by the stud, a helical spring within the sleeve connected at one end of the sleeve, a shiftable ring within the sleeve, pivoted to the stationary member and having the other end of the spring connected to it, a disk on said sleeve, one or more adjustable stops on the disk, a second disk having a series of ratchet teeth carried by said sleeve, operating and detent pawls coacting with the ratchet teeth, actuating mechanism for the operating pawl, repeat mechanism for causing successive actuations thereof, and 80 means operated by one of the stops coming to a certain position for terminating the operation of the repeat mechanism, and means for retracting both pawls from the ratchet teeth, enabling the spring to return the parts. 90

95 41. A tabulator mechanism having a movable member carrying one or more adjustable stops, an operating pawl for feeding said member step by step, repeat mechanism for causing successive actuations of said pawl, and means operated by one of the stops coming to a certain position for terminating the operation of the pawl, combined with an embossing mechanism having male and female dies, a letter feed for a ribbon of material 100 passing before such dies, and a keyboard for positioning the dies and controlling the operation of said letter feed, the letter feed being coupled with the repeat mechanism, means for restoring the tabulator to initial 105 position, and means for cutting off the embossed region, said cutting off means being connected with said restoring means.

110 42. The combination with means for holding oppositely acting pairs of embossing letter character dies, means for holding material to be embossed between such dies, mechanism for feeding one of said means with reference to the other a letter space at a time, and a settable tabulator mechanism adapted to 115 cause a selected number of operations of said mechanism.

120 43. The combination, with character impressing devices and means for operating the same, and mechanism for causing a single definite letter feed for various characters consequent upon such operation, of a tabulator mechanism having a key adapted to release it and initiate power to it to cause successive operations of the same letter feed, 125 said tabulator mechanism having a settable stop, and means whereby each operation of the letter feed brings the stop one step nearer

a definite point, and means operated by the stop arriving at the definite point for terminating the letter feed.

44. The combination with embossing mechanism having embossing dies movable to emboss material and a letter feed for feeding the material so that successive embossing actions take place relative to such material one letter space ahead of the preceding action, of a tabulator having a rotative disk provided with an adjustable stop automatically set one step by each operation of the letter feed, means associated with the tabulator for causing continuous operation of the letter feed, and means actuated by said adjustable stop coming to a definite position for stopping the continuous operation.

45. The combination with male and female

embossing dies and means for holding a ribbon of material extending between them, of mechanism arranged to actuate selective dies on each cycle of the machine and to cause relative feeding movement between the dies and material the same for each character embossed, and a tabulator means to cause by manually released power a preselected number of successive cycles of the same feeding mechanism, said tabulator means being settable to render selected dies active during such cycles and also settable to cause said relative movement only without embossing.

In testimony whereof, we hereunto affix our signatures.

LAWRENCE H. MORSE.
